UNITED STATES PATENT OFFICE.

THEODORUS S. BAILEY, OF QUINCY, MASSACHUSETTS.

MECHANISM FOR FIRING TORPEDOES.

1,094,963.

Specification of Letters Patent.

Patented Apr. 28, 1914.

Application filed October 25, 1910. Serial No. 589,002.

To all whom it may concern:

Be it known that I, THEODORUS S. BAILEY, a citizen of the United States, having a residence and post-office address at Quincy, 5 Massachusetts, have invented certain new and useful Improvements in Mechanism for Firing Torpedoes; and I do hereby declare the following to be a full, clear, and exact description of the invention, such as will 10 enable others skilled in the art to which it appertains to make and use the same.

The invention relates to improvements in mechanism for firing torpedoes, and is particularly applicable to installations in which 15 it is desired that the firing of the torpedoes may be controlled from one or more distant stations, and in which the torpedoes are discharged by admitting into the discharge tube, back of the torpedo, air or other suitable fluid under pressure.

The particular nature and specific object of the invention will best be understood from the following description when read in connection with the accompanying drawings, 25 which illustrate the preferred form of the invention applied to a torpedo tube installation of well known character, such as is now commonly used in submarine boats of the United States Navy.

In the drawings: Figure 1 is a front elevation of a set of four torpedo tubes arranged in the end of a submarine boat, the tubes being equipped with improved firing and controlling mechanism in accordance 30 with the present invention; Fig. 2 shows in side elevation one pair of the torpedo tubes and the associated controlling and firing mechanism, as well as mechanism of standard type for turning the torpedo tube cap to open and close the tubes; Fig. 3 illustrates a control station, and in this case shows the arrangement of control valves in proximity to the lower end of the periscope tube of a submarine boat, the control 35 valves being within easy reach of an observer standing at the eye-piece of the periscope; Fig. 4 is a front elevation, partly in section, showing the expulsion valve, and the distributing valve in their relation to the upper torpedo tube of each set, the main air supply pipe with its two branches and 40 controlling valves being removed, to simplify the illustration; Figs. 5 and 6 are respectively a central vertical section and a 45 plan view of the expulsion valve and associated piston valve for removing the stop-

bolt from the path of the torpedo; Fig. 7 is a central vertical section of one of the control valves located at the control station; Fig. 8 is a central vertical section of a distributing valve, the gearing whereby the distributing valve is actuated from the shaft of the torpedo tube cap being shown in elevation; Fig. 9 is a section on the line 9—9 of Fig. 8; Fig. 10 is a central vertical section, partly broken away, of a submarine boat, showing in a diagrammatic manner the relation of the apparatus of the present invention to the torpedo installation and observation periscope of a submarine boat; and Fig. 11 is an end view of the rotary torpedo-tube cap.

The arrangement of the four torpedo tubes, as shown in Figs. 1, 2, and 10 is according to the standard practice of the 50 United States Navy, and since this arrangement forms no part of the present invention, it is unnecessary to describe it further than to point out that the forward ends of the torpedo tubes are opened and closed by means of a rotatable cap 76 actuated by the shaft 75, substantially as shown and described in United States Letters Patents to Hugo E. Grieshaber, No. 820,925, of May 15, 1906. The cap operating shaft 75 is centrally located with respect to the four tubes, 1, 2, 3, and 4, and carries a gear segment 5, which is adapted to be turned, by means of the handle 6 and pinion 7, so as to bring the passages 77 in the cap into registry with and to thereby open tubes 1 and 4 or 2 and 3, depending upon the direction in which the cap is turned. The upstanding arm 8, and its actuating mechanism including the hand-wheel 9, seen in Fig. 2, are provided for the purpose of giving fore and aft motion to the cap, thus enabling it to be drawn up tightly on the gaskets around the outboard ends of the tube. The air or other compressed fluid comes from the pressure tank 100 (not shown) to the two sets of torpedo tubes through the pipe 10, elbow 11, and the branch conduits 12 controlled by valves 13, into the valve chambers of the four expulsion valves. This construction will best be 105 understood from Figs. 1, 2, 4 and 6, it being remembered that in Figs. 4 and 6 the main air supply pipe with its two branches and valves 13 are removed. From these figures it will be seen that the elbows 11 with their 110 branch conduits 12, stand upon the flat flanges 15 which surround the passage to

the valve chamber 14 of the expulsion valve. There are four expulsion valves, one for each of the torpedo tubes, and though all four of them are mounted on the upper surfaces of the two upper torpedo tubes, each one is secured to a box-like casing 16, the two casings on the inner sides of the torpedo tubes 1 and 3 communicating directly with those tubes, and the two outer casings communicating respectively with the tubes 2 and 4 through the conduits 17 (see Figs. 1, 2 and 5).

10 The particular form of expulsion valve shown in the drawings forms no part of the present invention, but is of the type disclosed and claimed in the United States patent to Gregory C. Davison, Number 1,003,993, and the construction will be understood from Figs. 5 and 6, which show 20 this part of the mechanism in detail.

Within the casing 14 of each expulsion valve is a stem 18 carrying at one end the main valve 19, which controls the passage to the torpedo tube, and at the other end a 25 differential element such as a diaphragm or piston 20, so that the air or other fluid under pressure is admitted to the valve chamber between the main valve 19 and the differential piston. The exposed area of the differential piston is preferably somewhat larger than the exposed area of the valve 19, so that the pressure from the main reservoir tends to hold the valve 19 to its seat. It is, however, convenient to provide, for the 30 purpose of assisting in this effect, a coiled spring 21 surrounding the valve stem and tending to seat the main valve 19. Above the expulsion valve, and in a casing which may be formed in the same casting, is a piston valve 22, normally spring pressed by the 35 spring 23 into the position shown in Fig. 5 of the drawing. This piston valve controls the duct 24 which leads to the valve casing 14 at the rear of the differential piston 20, and its stem 25 is connected through the 40 rod 26 with the mechanism commonly employed in connection with torpedo tube firing mechanism for withdrawing from the path of the torpedo a stop bolt which projects into the torpedo tube and lies in the 45 path of the torpedo. Stop bolts of this character are widely used and are fully illustrated and described in U. S. Letters Patent to Lawrence Y. Spear, No. 871,453, 50 of November 19, 1907, for example, and, as will be understood by those skilled in the art, it is necessary to remove such stop from the path of the torpedo before the torpedo is discharged.

60 Associated with the above described apparatus and adapted to determine the movements of the piston valves 22, to thereby control the firing of the torpedoes, is a system of pressure pipes leading to the distant 65 control station or stations. It will be ob-

served that tapped into the head of the casing of each of the piston valves 22, is a small pressure pipe, these pipes being numbered 27, 28, 29 and 30 on the drawing. It would be feasible to lead each of said pipes 70 directly to the distant control station, and provide each of them, at that station, or at each of the distant stations, with a control valve, and such an arrangement is, broadly considered, within the scope of the 75 present invention. For the purpose of simplifying the system and adding to the safety thereof, however, I provide two distributing cocks 31 and 32, together with mechanism for actuating said cocks from the cap actuating shaft, in a manner which will be hereinafter described more in detail, and lead the two pressure pipes 27 and 28 to one of the cocks and the two pressure pipes 29 and 30 to the other cock. From each of 80 the cocks there extends to the distant control station or stations, a pressure pipe, those pipes being indicated by the reference numerals 33 and 34 on the drawings. A distant control station at the eye-piece of the 85 periscope tube is indicated in Fig. 10, and shown in detail in Fig. 3, and it will be observed that each of the pipes 33 and 34 leads to a separate control valve 35 and 36 respectively. Each of the control valves is 90 connected, by the pipe 37, to a source of air or other fluid under pressure, such a source being always available on a submarine boat or wherever torpedoes are to be discharged by such fluid. The pipe 37 is preferably 95 provided with a shut-off cock 38 adapted to control the connection with the source of pressure. The valves 35 and 36 are of identical construction, and one of them is shown in detail in Fig. 7, from which it will be 100 seen that the valve is supported on a plate about the lower end of the periscope tube, and which forms part of the support for said tube. As will be understood by those skilled in the art, many types of valves are 105 suitable for this purpose, but the particular one illustrated comprises a piston 59 sliding in a short pipe section 39, and normally pressed by the spring 40 into the closed position as illustrated in Fig. 7. The 110 stem 41 of the valve extends upwardly through a gland 42 and is connected by the pin 43 to the lever arm 44 pivoted at 45 on the upstanding bracket 46. Connected to the outer end of the lever arm 44 is a pull rod 115 47 passing down through the plate on which the valve is supported and terminating in a handle 48 in position to be conveniently manipulated by the observer at the periscope tube. The periscope here shown is of the binocular type which is now in use in the United States Navy and is mounted for rotation in the manner indicated in Fig. 3, from which it will be seen that the periscope tube 60 passes through the plate 61, which 120

125 130

supports the control valves 35 and 36 and the tube has below the plate the ordinary eye-piece portion 62, together with an annular gear 63 surrounding the tube and fixed 5 to the plate 61. The eye-piece portion carries a bearing sleeve 64 for a stub shaft which has at its upper end a pinion 65 and at its lower end a hand-wheel 66, so that by turning the hand-wheel the periscope tube may be rotated. This type of periscope tube is shown and described in United States Letters Patent to G. C. Davison, No. 970431, dated Sept. 13, 1910, and is used in connection with a direction indicator so constructed 15 that when the axis of the boat coincides with the direction in which the torpedo is to be fired, an alarm is sounded as an indication of the instant when the torpedo should be fired.

20 The details of the distributing cocks will be understood from Figs. 8 and 9 which show in detail one of the cocks and its actuating mechanism. Each of these devices comprises a conical plug 49 fitted into a casting 50 and spring pressed to its seat by the coiled spring 51. The shaft of the plug extends through the hub of a gear segment 52, which is splined to the shaft, and then through a bearing in the bracket 53. Fixed 25 to the end of the shaft is a quadrant 55 meshing with pinion 56 on the shaft of the cap actuating handle 6 (see Figs. 2, 4 and 8.) The plug 49 contains a duct 57 which, in the position indicated in Fig. 9, which 30 corresponds to the closed position of the cap, is out of communication with all of the pipes 27, 28 and 33 which are tapped into the casting 50. When the handle 6 is rotated to turn the cap in one direction or the other, 35 segment 55 is caused to rotate by pinion 56, and the middle gear of train 58 being keyed to the segment shaft is also caused to turn, thus imparting circular motion through the other gears of train 58 to the quadrants 52, 40 which are keyed to the plug shafts. (See Fig. 4.) If the handle 6 is turned in a clockwise direction, as seen in Fig. 1, the gear segment 5 is turned to the left. This movement turns the gear segment 55, and the 45 shaft to which it is keyed, to the right, as viewed in Fig. 4, and through the intermediate gear of the train 58, and the two idle gears, turns both segments 52 in a counter-clockwise direction as viewed in that figure. 50 This turns the plugs of cocks 31 and 32 in a counter-clockwise direction as viewed in Fig. 4, and will put pipe 28 into communication with pipe 33, and pipe 30 into communication with pipe 34, the ducts in the plugs of 55 cocks 31 and 32 being properly arranged for that purpose. It will be seen that by this construction the control valves 35 and 36 are automatically put into communication with those torpedo tubes which are open and 60 ready for firing. If the handle 6 had been

rotated in the other direction the tubes 2 and 3 would have been opened and the plugs of cocks 31 and 32 moved in such direction as to put the pipes 33 and 34 into communication with the pipes 27 and 29 respectively. 70 It will be understood that when this opening of the cap has been effected, and the valves 13 have been opened, two of the tubes are ready for firing, one of them being under the control of the control valve 35 and the other under the control of the control valve 36. The man at the observing station has now complete control of the firing of the torpedoes, and when he observes that the torpedo tube is properly aimed he pulls one of the handles 48 to fire the corresponding torpedo. If, for example, he pulls the handle of the valve 35 the fluid under pressure passes from the reservoir through the control pipe 33 and the distributing cock 31 to the pipe 28, and into the valve chamber of piston valve 22 on tube 1. The fluid under pressure moves piston 22 to the right as seen in Fig. 5, withdrawing the torpedo stop bolt and opening the passage 24, whereupon the pressure fluid flows into the valve chamber of the expulsion valve back of the differential piston 20, and forces valve stem 18 to the right and valve 19 off its seat, thereby admitting the pressure in chamber 14 to the 80 torpedo tube and discharging the torpedo. 85

90 It will be observed that the installation above described embodies many details of construction which in themselves are capable of considerable mechanical variation, and though the preferred form embodies an arrangement in which the control is effected by means of air or other fluid under pressure, nevertheless it is broadly new, so far as I am aware, to provide a connection between the tube-opening means and the firing mechanism of a plurality of torpedoes such that the movement of the tube-opening means automatically renders inoperative the controlling mechanism for those firing devices 100 associated with the closed torpedo tubes, and simultaneously renders effective the controlling devices of the firing mechanism of those torpedo tubes which have been opened. Obviously such connection is applicable whether 105 the firing-control is effected by means of fluid pressure or otherwise. I also believe it to be broadly new to associate controlling devices for a plurality of torpedo firing means with the periscope of a submarine boat, in 110 such manner that the controlling devices may be conveniently manipulated by the observer at the periscope. 115

120 Having thus described my invention what I claim is:

1. A torpedo tube installation comprising a plurality of tubes having tube opening mechanism and firing mechanism associated therewith, in combination with connections between the tube opening mechanism and the 130

firing mechanism, such that the actuation of the tube opening mechanism automatically renders inoperative the firing mechanism of the closed tubes and renders operative the firing mechanism of the opening tube; substantially as described.

2. A torpedo tube installation comprising a plurality of tubes having tube opening mechanism and firing mechanism associated therewith, in combination with a firing control device common to a plurality of the firing mechanisms and connections between the tube opening mechanism and said firing control device, such that the actuation of the tube opening mechanism automatically connects the firing control to the open tube; substantially as described.

3. In mechanism for firing torpedoes from any one of a plurality of tubes having cap-operating means adapted to open less than the whole number of tubes, an expulsion valve for each tube, in combination with controlling mechanism for said valves, and connections between the cap-operating means and the controlling mechanism adapted to automatically disconnect the controlling mechanism from the closed tubes and connect it with the open tube or tubes; substantially as described.

4. A torpedo tube installation comprising a plurality of tubes having tube opening mechanism and firing mechanism associated therewith, in combination with a plurality of firing control devices located at a distant station and of less number than the number of tubes and intermediate connections responsive to the movement of the tube opening mechanism and adapted to automatically connect a distant firing control device to the firing mechanism of each open tube; substantially as described.

5. In mechanism for firing torpedoes from any one of a plurality of tubes having means adapted to open less than the whole number of tubes, an expulsion valve for each tube, controlling means therefor located at a distant station, and connections between said means and the expulsion valves, said connections including mechanism responsive to the movement of the tube-opening means and adapted to automatically disconnect the controlling means from the closed tubes and connect it with the open tube or tubes; substantially as described.

6. In mechanism for firing torpedoes from any one of a plurality of tubes having cap-operating means adapted to open less than the whole number of tubes, an expulsion valve for each tube, a control valve and connections between the control valve and the expulsion valves, said connections including a distributing valve connected to the cap operating means and adapted to automatically connect the control valve with

the open tube and disconnect it from the remainder of said tubes; substantially as described.

7. In mechanism for firing torpedoes from any one of a plurality of tubes, having a cap-operating means adapted to open less than the whole number of tubes, an expulsion valve for each tube, connections for actuating the expulsion valves including a distributing valve connected to the cap-operating means and controlling the connections to a plurality of tubes, a pressure pipe extending from the distributing valve to a distant station and a control valve for said pipe at the distant station, said distributing valve being so connected as to automatically connect the control valve to the open tube and disconnect it from the remainder of said tubes; substantially as described.

8. In mechanism for firing torpedoes from any one of a plurality of tubes having means adapted to open less than the whole number of tubes, an expulsion valve for each tube having a main valve controlling communication with the tube, an equalizing element connected to the stem of said valve, and connections for admitting fluid under pressure between the main valve and the equalizing element, in combination with connections for admitting fluid under pressure to the other side of each of the several equalizing elements to open the main valves, said last named connections including control pipes extending to a distant control station, valves at said station for admitting pressure fluid to said pipes, and connections between the tube-opening means and said pipes adapted to automatically connect the control pipes to the valves of the open tubes; substantially as described.

9. In a mechanism for firing torpedoes from any one of a plurality of tubes having cap-operating means adapted to open less than the whole number of tubes, an expulsion valve for each tube having a main valve controlling communication with the torpedo tube, an equalizing element connected to the stem of said valve, and connections for admitting fluid under pressure between the main valve and the equalizing element, in combination with connections for admitting fluid under pressure to the other side of each of the several equalizing elements to open the main valves, said connections including control pipes extending to a distant control station, valves at said station for admitting pressure fluid to said pipes, and connections between the cap operating means and said pipes adapted to automatically shut off connection between the control pipes and the valves of the closed tubes and open connection between the said pipes and the valves of the open tubes; substantially as described.

10. In mechanism for releasing and firing

a torpedo from its tube, an expulsion valve for the tube having a main valve controlling communication with the tube, an equalizing element connected to the stem of said valve, connections for admitting fluid under pressure between the main valve and the equalizing element, connections for admitting fluid under pressure to the other side of said equalizing element to open 5 the main valve, said connections includ-

ing a piston adapted to be connected to the torpedo stop-releasing mechanism, and a control valve in said last named connections; substantially as described.

In testimony whereof I affix my signature, 15
in presence of two witnesses.
